CLAIM

The ornamental design for a display screen with ride sharing icon, as shown and described.

DESCRIPTION

FIG. 1 is a front view of a display screen with ride sharing icon; and,

FIG. 2 is a view of the display screen with ride sharing icon, shown on a device.

The broken lines in FIG. 2 are included for the purpose of showing portions of the article which form no part of the claimed design.

1 Claim, 2 Drawing Sheets**FIG. 1**

FIG. 2
